OIL CAN OPENER

John W. Sherrell, Roswell, N. Mex.

Application January 24, 1938, Serial No. 186,721

3 Claims. (Cl. 221—23)

This invention relates to a sealed container opener and has for the primary object the provision of a simple, durable and efficient device of this character which embodies a construction 5 wherein a sealed container may readily have a side wall thereof penetrated or opened for the emptying of the contents into the device so that the latter may be employed for directing said contents into another device without danger of 10 spilling or waste, the container being opened by the destruction of a side wall thereof to prevent said container from being restored for further use.

With these and other objects in view, this invention consists in certain novel features of construction, combination and arrangement of parts 15 to be hereinafter more fully described and claimed.

For a complete understanding of my invention, reference is to be had to the following description 20 and accompanying drawing, in which

Figure 1 is a vertical sectional view illustrating an opener constructed in accordance with my invention and showing a container opened thereby.

Figure 2 is a transverse sectional view illustrating the same.

Figure 3 is a top plan view illustrating the device.

Referring in detail to the drawing, the numeral 1 indicates a funnel including a spout 2 and a flared portion 3. The walls of the flared portion 3 of the funnel are extended to form a substantially rectangular shaped container receiving portion 4 opposite end walls of which have integral therewith hook-shaped finger pieces 5 which may be employed for supporting the device on another device if desired. The interior dimensions of the portion 4 are such to permit a sealed container 6 to be placed therein upon one of its sides, the end walls of the container being arranged adjacent to the end walls of the portion 4. Spaced bars 7 are integral with opposite end walls of the portion 4 slightly above the flared portion 3 of the funnel and have integral therewith vertically arranged penetrating elements 8 spaced a selected distance apart and are adapted to form in a wall of the container 6 spaced openings when said container is pushed downwardly in the portion 4 of the device allowing the contents of the container to drain into the funnel 1 and thence into another device to which the funnel is adapted. The penetrating elements 8 are preferably of tubular formation having their upper ends cut on a bevel to provide penetrating points A and cutting edges B. The penetrating points 55 A when passing through the wall of the container

along with the cutting edges B curve the material of the wall inwardly and away from the upper end of the penetrating element so that the contents of the container may flow freely therefrom, also the penetrating elements acting to admit atmospheric air into the container to facilitate the flow of the contents out of the container into the funnel. The opening of the container by the destruction of a side wall thereof prevents the container being restored for further use. If the 10 container is opened by puncturing an end wall said end wall can be easily removed and replaced by another reconditioning the container for further use. Thus it will be seen that the present invention has a distinct advantage over similar 15 openers in that it renders the container unfit for further use after being opened thereby.

What is claimed is:

1. An opener comprising a funnel including a spout and a flared portion, said flared portion 20 having its walls extended to form a substantially rectangular shaped container receiving portion adapted to receive a container disposed upon its side, spaced bars integral with opposite walls of the container receiving portion, and tubular penetrating elements carried by the spaced bars and having ends beveled to form combined penetrating points and cutting edges to sever a side wall of a container as it is placed in the container receiving portion.

2. An opener comprising a funnel including a spout and a flared portion, said flared portion having its walls extended to form a substantially rectangular shaped container receiving portion adapted to receive a container disposed upon its side, spaced bars integral with opposite walls of the container receiving portion, tubular penetrating elements carried by the spaced bars and having ends beveled to form combined penetrating points and cutting edges to sever a side wall of a 35 container as it is placed in the container receiving portion, and hook-shaped finger pieces integral with opposite walls of the container receiving portion and arranged exteriorly of the latter.

3. An opener for a sealed container comprising a rectangular shaped portion including solid walls and open at the top and bottom thereof whereby a container disposed on its side may be placed in said portion from the top thereof, a funnel including a flared portion formed on the lower edges of 40 the solid walls, and means mounted in the rectangular shaped portion to destroy a side of the container as the latter is placed in said rectangular shaped portion.
